United States Patent Office

Des. 185,270
Patented May 26, 1959

185,270

CLOTHESPIN

Norman Exton, Sands Point, N.Y., assignor to Atlantic Wire and Cable Corporation, College Point, N.Y., a corporation of New York

Application January 20, 1959, Serial No. 54,248

Term of patent 14 years

(Cl. D17—3)

I claim:

The ornamental design for a clothespin, substantially as shown.
